ARTIFICIAL TEETH

Walter D. Raber, Chicago, Ill.

Application October 4, 1948, Serial No. 52,661

4 Claims. (Cl. 32—8)

1

The present invention pertains to the posterior or masticating teeth of artificial dentures including the upper and lower bicuspids or premolars as well as the first and second molars and does not extend to the anterior teeth including the incisors and canine teeth.

As is well known, users of artificial dentures are handicapped inevitably by having available masticating pressures that are only a small percentage of the corresponding pressures that can readily be developed with natural teeth; for example, with artificial dentures, the pressures usually available do not exceed from ten to forty pounds, whereas with natural teeth, pressures up to two hundred pounds and even more, may readily be developed. Obviously, occlusal surfaces well adapted to the requirements of effective and efficient mastication with such high pressures, as in natural teeth, cannot be relied upon and cannot produce satisfactory and efficient results at the lower pressures referred to, where the teeth of artificial dentures are given the form of occlusal surfaces found in natural teeth. Many attempts have been made to compensate for the great difference in pressures referred to, by making artificial teeth with occlusal surfaces that will more efficiently effect mastication at low pressures, but such attempts have been open to more or less objection, either because of complication and expense in manufacture, or inefficiency in use, or both.

It is the object of the invention to overcome the difficulty referred to by providing the occlusal surfaces of the posterior artificial teeth with masticating areas much less than found in corresponding natural teeth, so that the small pressures available will cause effective penetration of said smaller areas into the food being masticated, and at the same time so firmly hold the food between the upper and lower teeth, that the mandibular action accompanying mastication, will cut, tear and shred the food, and so accomplish its maceration. To effect this result in accordance with the invention, the occlusal surfaces of the teeth of one denture, for example, the upper denture, are each provided with spaced transverse ribs having cutting edges and separated by depressions or valleys for the reception of food pressed into them, which ribs and valleys are preferably straight and parallel to facilitate manufacture. The occlusal surfaces of the teeth of the other denture, for example, the lower denture, are each provided with a longitudinal rib and cutting edge substantially parallel with and spaced from the buccal surface of the tooth, and

2

having a longitudinal depression or valley extending medially across the occlusal surface and defining said rib or cutting edge. This depression or valley is of progressively decreasing depth from said rib towards the lingual surface of the tooth and merges with the occlusal surface thereof before reaching said lingual surface. Said rib and valley are preferably straight and parallel to facilitate manufacture.

- 10 With the construction described, the buccal surfaces of the artificial teeth have substantially the same appearance as natural teeth, and there is no increased danger of cheek bite, because the marginal portions of the occlusal surfaces of the teeth adjacent their buccal surfaces, have the same cuspal form as found in natural teeth.
- 15 Again, the lingual surfaces of the teeth of the invention, and the adjacent marginal portions of the occlusal surfaces thereof, have the same appearance and form as natural teeth, protecting the tongue from increased danger of biting, and not interfering in any way with the functioning of the tongue during mastication, in shifting the food from place to place between the teeth.
- 20
- 25 With the dentures of the invention coacting in use, the preferably straight ribs and valleys of the teeth of one denture cross the preferably straight ribs and valleys of the teeth of the other denture at substantially right angles, the crossed ribs of any two coacting teeth are pressed even with small pressure through the food and nearly or quite into engagement with each other over small areas, adjacent parts of the food are firmly pressed into and held in the crossed valleys, and
- 30
- 35 the mandibular action of the teeth effectively cuts, shreds and tears the food to efficiently masticate it.

Where the teeth of the invention are made of hard and wear-resistant material such as porcelain, extremely hard plastic and the like, reinforcing means for the ribs may not be required; it has heretofore been proposed however, to make artificial teeth of material softer and less wear-resistant than are said hard materials, for example, plastic material, and the invention provides an effective tooth construction of such softer material, adapted particularly to meet the requirements of some cases with very limited masticating pressure, by using sheet inserts of suitable metal or metallic alloy, to form the described ribs and cutting edges of the teeth, which inserts are preferably incorporated in the teeth during their manufacture.

Any known techniques and materials may be used in making the teeth of the invention, and

in mounting them on suitable bases to form the dentures of the invention.

The invention includes teeth constructed as described and also dentures incorporating said teeth in their structures, and it is the object of the invention to produce artificial teeth and dentures having the structure, mode of operation and results described.

The invention will be best understood by reference to the accompanying drawings illustrating preferred embodiments thereof, in which

Fig. 1 is an occlusal plan view of an upper denture in accordance with the invention,

Fig. 2 is an occlusal plan view of a lower denture in accordance with the invention, adapted to cooperate with the denture shown in Fig. 1,

Fig. 3 is a vertical sectional view to an enlarged scale, through the first molar shown to the right in Fig. 1, this view being taken along the line 3—3 in Fig. 1,

Figs. 4, 5 and 6 are vertical, sectional views of the structure shown in Fig. 3, taken respectively along the lines 4—4, 5—5 and 6—6 in Fig. 3.

Fig. 7 is an occlusal view of the molar shown in Fig. 3.

Fig. 8 is a vertical, sectional view to an enlarged scale, through the first molar shown to the right in Fig. 2, this view being taken along the line 8—8 in Fig. 2.

Figs. 9, 10 and 11 are vertical, sectional views of the structure shown in Fig. 8, taken respectively along the lines 9—9, 10—10 and 11—11 in Fig. 8,

Fig. 12 is a top plan view of the molar shown in Fig. 8,

Figs. 13, 14 and 15 show in views respectively like Figs. 3, 4 and 7, a modified construction of upper first molar having metal inserts, and

Figs. 16 and 17 show in views respectively like Figs. 8 and 12, a modified construction of lower first molar having metal inserts for coaction with the first molar shown in Figs. 13, 14 and 15.

Similar numerals refer to similar parts throughout the several views.

In several of Figs. 3 to 17 inclusive, the letters L and B are employed to respectively indicate the lingual and buccal sides of the teeth illustrated.

The upper denture illustrated in Fig. 1, includes a base 1 mounting anterior teeth including incisors 2 and canines 3, and also posterior teeth including right and left bicuspids 4a, first molars 5 and second molars 6.

The lower denture illustrated in Fig. 2, includes a base 1a mounting anterior teeth including incisors 2a and canines 3a, and also posterior teeth including right and left bicuspids 4a, first molars 5a and second molars 6a.

Only the posterior teeth referred to and variants thereof, and their coaction are involved in the present invention.

As shown in Fig. 1, the first molar 5 at the right, has its occlusal surface transversely crossed by continuous straight parallel and spaced ribs 7 having a depression or valley 8 between them, similar depressions 9 being longitudinally formed in the occlusal surface of the tooth outside of said ribs 7. The occlusal surfaces of the ribs 7 are, preferably in the same plane connecting the apices of the cusps of the molar 5. The formation of the ribs 7 and depressions 8 and 9 is better shown in Figs. 3, 4 and 7. It will be noted that the lower edges of the ribs 7 are relatively sharp and form cutting edges for food pressed upwardly against the ribs, and that the depressions 8 and 9 form hollows or cavities for receiving without

undue pressure, parts of food pressed upwardly above said cutting edges (see Fig. 4).

As shown in Fig. 2, the first molar 5a at the right, has its occlusal surface longitudinally crossed by a rib 7a joining the apices of the cusps of the molar 5a on the buccal side of the tooth, the medial portion of the occlusal surface of the molar having a longitudinal depression 8a therein extending entirely across the tooth adjacent to and parallel with the rib 7a and of a form making the adjacent surface of said rib substantially perpendicular to the occlusal surface of the tooth, and defining with the occlusal surface of said rib, a relatively sharp cutting edge extending longitudinally entirely across the tooth. The formation of the rib 7a and depression 8a and their relation to each other are more clearly shown in Figs. 8, 9 and 12.

It will be noted that the buccal margin of the 20 occlusal surface of the rib 7a shown in Figs. 8 and 12, has substantial width which is unbroken longitudinally of said surface although said margin has small area. When, in the mastication of food, said marginal area coacts with the 25 corresponding bucco-marginal area of the molar 5 shown in Figs. 3 and 7, which is also unbroken longitudinally, the small area of the rib 7a with but small applied pressure, effectively penetrates a small part of the food until said rib is nearly 30 or quite in engagement with the corresponding bucco-marginal portion of the occlusal surface of the molar 5; at the same time, the lingo-marginal areas of the occlusal surfaces of the molars 5a and 5 similarly coact on another small 35 part of the food between said molars; by the action described, the food between said molars is firmly held against lateral displacement, and parts of said food are pressed into the depressions 8, 9 and 8a with a substantial amount of cutting 40 thereof by the edges of the ribs 7 and 7a, which edges are thus brought nearly or quite into engagement with each other; with the food so held between the molars 5a and 5, mandibular movement of the teeth effectively cuts, shreds and tears said food by the action of said ribs, to efficiently masticate the food.

The walls and bottoms of the depressions 8, 9 and 8a are preferably inclined and rounded to avoid pockets in which the food might be tightly 45 packed and held, to the end that during mastication the tongue may quite as effectively operate to re-distribute and move the food, as with natural teeth.

As shown in Figs. 5 and 6, the buccal and 50 lingual aspects of the molar 5 are respectively the same as with natural teeth, and the same is true for the molar 5a as shown in Figs. 10 and 11. This insures that the danger of cheek bite and tongue bite shall be no greater than with 55 natural teeth.

Each of the other upper posterior teeth shown in Fig. 1 is constructed in the same manner as the molar 5 described in connection with Figs. 3 to 7 inclusive, and each of the other lower posterior teeth shown in Fig. 2 is constructed in the same manner as the molar 5a described in connection with Figs. 8 to 12 inclusive; and the operation of each coacting pair of upper and lower posterior teeth is substantially the same as 60 above described for the right molar 5 of Fig. 1 and the right molar 5a of Fig. 2, to produce substantially the same results.

Figs. 13, 14 and 15 illustrate the construction of a first upper molar 5b of softer material than porcelain, for example, plastic material, corre-

sponding to the molar 5 described in connection with Figs. 3 to 7 inclusive, and where it is desirable to reinforce the ribs of the molar; and Figs. 16 and 17 illustrate the construction of a first lower molar 5c of material similar to the molar 5b, corresponding to the molar 5a described in connection with Figs. 8-12 inclusive, and where it is desirable to reinforce the rib of the molar.

The upper molar 5b illustrated in Figs. 13, 14 and 15 is of the same form and construction as the molar 5 shown in Figs. 3 to 7 inclusive, excepting that it may be made of material softer or weaker than porcelain, or both, for example, plastic material, and that its ribs 10 include thin sheet metal inserts made preferably of any metal or metallic alloy that is wear resistant and free from corrosion by the secretions of the mouth, for example, gold alloy, which inserts are embedded in the material of the molar 5b preferably during its manufacture, perpendicularly to the occlusal surface of the molar and with their lower edges in said occlusal surface to form the cutting edges of said ribs. In all other respects the molar 5b is of the same construction and operates in the same manner as the molar 5 shown in Figs. 3 to 7 inclusive.

The lower molar 5c illustrated in Figs. 16 and 17 is of the same form and construction as the molar 5a shown in Figs. 8 to 12 inclusive, excepting that it may be made of material as described for the molar 5b, and that its rib is defined as to its cutting edge by a thin sheet metal insert 11 of material like the inserts of the ribs 10, embedded in the material of the molar 5c preferably during its manufacture, perpendicularly to the occlusal surface of the molar and with its upper edge in said occlusal surface to form the cutting edge of the rib and to also form a side wall of the longitudinal depression 12 adjacent said rib. In all other respects the molar 5c is of the same construction and operates in the same manner as the molar 5a shown in Figs. 8 to 12 inclusive, and the coaction of the molars 5b and 5c is the same as above described for the molars 5 and 5a shown in Figs. 3 to 12 inclusive.

Where rib reinforcements as shown in Figs. 13 to 17 inclusive, are desirable for all of the posterior teeth, each of the upper posterior teeth is constructed as described for the molar 5b, and each of the lower posterior teeth is constructed as described for the molar 5c, and each pair of coacting upper and lower posterior teeth, operates during mastication in the manner above described for a pair of coacting upper and lower molars 5 and 5a constructed as described in connection with Figs. 3 to 12 inclusive.

Thus the invention provides forms of posterior tooth structures which can readily be manufactured by known techniques, and it further provides forms of occlusal surfaces for any pair of coacting upper and lower posterior teeth, that secure during mastication, effective penetration, cutting, shredding and tearing of the food with applied pressures readily procurable with artificial dentures.

Although the longitudinal ribs and depressions of the lower posterior teeth are above described in connection with Figs. 8 to 12 inclusive as substantially straight, they may where desired to more closely conform to the jaw curvature, be slightly curved to effect continuous alignment of said ribs and depressions throughout said posterior teeth, without departing from the invention.

Whereas the occlusal surfaces of the posterior

teeth of the invention are above described as being in a horizontal plane or planes, it is to be understood that to meet the requirements of different techniques and theories of mandibular movement, they may when desired be inclined to the horizontal or be located in curved surfaces according to the preference of the artificer, without departing from the invention.

It is also to be noted, although the transverse ribs and depressions are above described as carried by the upper posterior teeth, and the longitudinal ribs and depressions are above described as carried by the lower posterior teeth, that these relations may be reversed if preferred, that is, the rib and depression structures shown in Figs. 3 to 7 inclusive, 13, 14 and 15 may be carried by the lower posterior teeth, and the rib and depression structures shown in Figs. 8 to 12 inclusive, 16 and 17, may be carried by the upper posterior teeth, without departing from the invention, since the advantageous results of either relation are substantially the same as long as the tooth structure and coaction are substantially as shown and described.

While I have shown my invention in the particular embodiments above described, I do not limit myself thereto as I may employ equivalents thereof without departing from the scope of the appended claims.

Having thus described my invention, what I claim is:

1. In combination, upper and lower artificial dentures having pairs of posterior teeth the occlusal surfaces of which are formed in a manner to provide for small contact areas between pairs of coacting teeth to obtain strong cutting forces and large sluice-way areas, each of said teeth having buccal and lingual cusps disposed with their apexes substantially in a plane, one of each pair of said teeth having two continuous straight parallel and spaced ribs extending transversely of its occlusal surface intermediate the buccal and lingual cusps and terminating in cutting edges slightly above the position of natural cusp anatomy and a depression between and parallel to said ribs, the other of each pair of said teeth having a single, substantially straight rib extending longitudinally of its occlusal surface and adjacent its buccal surface and crossing the direction of said transverse ribs and terminating in a cutting edge slightly above the position of natural cusp anatomy, and a longitudinal depression adjacent said longitudinal rib and parallel therewith extending laterally across the medial portion of the occlusal surface, thereby providing contact between teeth of coacting dentures at points slightly beyond normal cusp contact.

2. In combination, upper and lower artificial dentures having pairs of posterior teeth the occlusal surfaces of which are formed in a manner to provide for small contact areas between pairs of coacting teeth to obtain strong cutting forces and large sluice-way areas, each of said teeth having buccal and lingual cusps disposed with their apexes substantially in a plane, one of each pair of said teeth having two continuous straight parallel and spaced ribs extending transversely of its occlusal surface intermediate the buccal and lingual cusps and terminating in cutting edges slightly above the position of natural cusp anatomy and a depression between and parallel to said ribs, the other of each pair of said teeth having a single, substantially straight rib extending longitudinally

of its occlusal surface and adjacent its buccal surface and crossing the direction of said transverse ribs and terminating in a cutting edge slightly above the position of natural cusp anatomy, and a longitudinal depression adjacent said longitudinal rib and parallel therewith extending laterally across the medial portion of the occlusal surface, thereby providing contact between teeth of coating dentures at points slightly beyond normal cusp contact, said longitudinal depression being of progressively decreasing depth towards and terminating adjacent the lingual surface of said other tooth, thereby providing for free movement of food transversely as well as longitudinally of said posterior teeth.

3. In combination, upper and lower artificial dentures having pairs of posterior teeth the occlusal surfaces of which are formed in a manner to provide for small contact areas between pairs of coating teeth to obtain strong cutting forces and large sluice-way areas, each of said teeth having buccal and lingual cusps disposed with their apexes substantially in a plane, one of each pair of said teeth having two continuous straight parallel and spaced ribs extending transversely of its occlusal surface intermediate the buccal and lingual cusps and terminating in cutting edges slightly above the position of natural cusp anatomy and a depression between and parallel to said ribs, the other of each pair of said teeth having a single, substantially straight rib extending longitudinally of its occlusal surface and adjacent its buccal surface and crossing the direction of said transverse ribs and terminating in a cutting edge slightly above the position of natural cusp anatomy, and a longitudinal depression adjacent said longitudinal rib and parallel therewith extending laterally across the medial portion of the occlusal surface, thereby providing contact between teeth of coating dentures at points slightly beyond normal cusp contact, said ribs forming said cutting edges comprising metallic inserts merging at their ends into said cusps.

4. In combination, upper and lower artificial dentures having pairs of posterior teeth the oc-

clusal surfaces of which are formed in a manner to provide for small contact areas between pairs of coating teeth to obtain strong cutting forces and large sluice-way areas, each of said teeth having buccal and lingual cusps disposed with their apexes substantially in a plane, one of each pair of said teeth having two continuous straight parallel and spaced ribs extending transversely of its occlusal surface intermediate the buccal and lingual cusps and terminating in cutting edges slightly above the position of natural cusp anatomy and a depression between and parallel to said ribs, the other of each pair of said teeth having a single, substantially straight rib extending longitudinally of its occlusal surface and adjacent its buccal surface and crossing the direction of said transverse ribs and terminating in a cutting edge slightly above the position of natural cusp anatomy, and a longitudinal depression adjacent said longitudinal rib and parallel therewith extending laterally across the medial portion of the occlusal surface, thereby providing contact between teeth of coating dentures at points slightly beyond normal cusp contact, said longitudinal depression being of progressively decreasing depth towards and terminating adjacent the lingual surface of said other tooth, thereby providing for free movement of food transversely as well as longitudinally of said posterior teeth, said ribs forming said cutting edges comprising metallic inserts merging at their ends into said cusps.
